UNITED STATES PATENT OFFICE.

FRITZ ARTHUR ANDERSON, OF MILTON, WISCONSIN.

HINGE-JOINT.

1,144,090.

Specification of Letters Patent. Patented June 22, 1915.

Application filed March 11, 1914. Serial No. 823,869.

To all whom it may concern:

Be it known that I, FRITZ ARTHUR ANDERSON, a subject of the King of Sweden, and a resident of Milton, county of Rock, and 5 State of Wisconsin, have invented certain new and useful Improvements in Hinge-Joints, of which the following is a specification.

This invention relates to hinge-joints, and 10 more particularly to that class in which the joint comprises a pair of relatively movable hinge members, each having a roll portion one concentric within the other, and which does not require a pintle proper.

15 The main objects of this invention are to provide an improved form of hinge-joint which shall be substantially frictionless in operation; which shall be adapted to serve as a dust-tight and light-tight joint; which 20 shall be adapted for being formed mainly from sheet metal; which shall be convenient to assemble, and which shall be adapted to swing through a broad angular range.

An illustrative embodiment of this invention is shown in the accompanying drawings, in which:

Figure 1 is an end view with the hinge members turned to an angle of 90° from each other. Fig. 2 is a similar view with the 30 hinge members turned into alinement 180° apart. Fig. 3 is a similar view with the hinge members turned to lie flat against each other. Fig. 4 is a side elevation with the front of the roll portions of the joint 35 broken away at one end along the line A—A of Fig. 2 to show the end thrust bearings, the screw for the end block being removed. Fig. 5 is a side view of the left hinge member shown in Fig. 4. Fig. 6 is a side view of 40 the right hinge member shown in Fig. 4. Fig. 7 is an axial section of the hinge along the line B—B of Fig. 2. Fig. 8 is a sectional view similar to Fig. 7 but showing a modification in which the anti-friction members 45 are omitted. Fig. 9 is a sectional view similar to Fig. 7 but showing both ends of a long hinge with the middle portion broken away and illustrating a further modification in which a single unitary stop member 50 is provided at each end. Fig. 10 is a side view of a long narrow hinge adapted to extend continuously along the edge of a door lid or other hinged object.

In the construction shown in Figs. 1 to 55 7, the hinge 1 comprises a pair of relatively

movable members 2 and 3 having coactive roll portions 4 and 5 respectively formed along their adjacent edges. End thrust stop means 6 are provided comprising a pair of blocks 7 and 8 disposed side by side coaxially 60 within the rolls and having circular runways 9 in their opposing faces for bearing balls 10 disposed therein. The inner roll 5 (see Fig. 3) which may be designated as the pintle-roll, is of semicylindrical shape with 65 its free edge or flange 14 turned diametrically inward for coaction against the inner surface of the outer roll 4, which may be designated as the knuckle-roll. The roll 4 is of substantially cylindrical shape and is 70 formed with a medial longitudinal offset 15 opposite from the shank portion 17 of the same hinge member, whereby the part of the roll adjacent to the edge 14 is inwardly set somewhat from the opposite part and 75 whereby oppositely facing inner and outer shoulders 19 and 20 are provided, which are adapted to serve as stops for the opposite edges 21 and 22 respectively of the pintle roll 5 in opening and closing the hinge. 80 The free edge 25 of the knuckle-roll is turned inward medially of its length and provides an end thrust shoulder 28 which serves as a stop for the inner stop block 7, which at times may have rotative sliding 85 contact therewith. The edge-flange 14 is somewhat shorter than the hinge and the inner block 7 is carried rigidly thereby, a slot 30 being provided in said block for receiving an end 31 of the flange 14. The 90 outer block 8 is secured within the knuckle roll by any suitable means as a screw 35. When thus assembled the parts are securely held in place with the bearing balls between the stop members. In the form shown the 95 members 2 and 3 have their shanks 17 and 17' formed flat. It will be understood that the said shanks may constitute the walls of a box or the like as illustrated in Fig. 10, or may be of any desired form.

100 In the construction shown in Fig. 8 the stop blocks 46 and 47 are mounted in the same way respectively as blocks 7 and 8 and are similar thereto except that no ball-races or balls are provided. For some purposes 105 this form will answer all practical requirements substantially as well as the anti-friction form having ball bearings.

In the construction shown in Fig. 9 the hinge is provided with a pair of stop blocks 110

one at each end, similar to each other and to the blocks 47 shown in Fig. 8, no inner blocks being used. In this instance the ends of the inwardly turned flanges 14 and 25 are both adapted at their ends for rotative contact with the blocks 47, and the inwardly turned flange 25 on the knuckle roll may be omitted, its presence not being required as the end blocks 47 and the flange 14 10 on the pintle roll serve to prevent longitudinal movement. The provision of stop means at both ends is especially desirable where the hinge joint is very long, as in case it is used to provide a continuous hinge-joint for extending along the whole length of the edge of a door or lid for rendering the same light and dust tight. Moreover, the end stops impart a neat and finished appearance by closure of the openings at the ends 15 of the rolls.

Concentric alinement of the rolls throughout their length is maintained by the overlapping of the rolls 4 and 5 and the co-operative action of the flange 14.

25 The hinge parts may be assembled as follows: The block 7 is placed upon the end of the flange 14. The hinge rolls are then telescoped together and the outer block 8 inserted into the knuckle roll with the bearing balls in place, and is secured by means of the screw 35.

The operation of the hinge is as follows: When the members are opened from the closed position shown in Fig. 3 the rolls 35 slide concentrically past each other and the free edge of the flange 14 slides over the inner surface of the knuckle roll 4, thereby assisting to hold the pintle roll in place. When the hinge is opened to its full extent, 40 the shank edge of the pintle roll is arrested by the stop shoulder 20. When the hinge is closed as shown in Fig. 3 the free edge of the pintle roll contacts with the inner shoulder 19 and the shank 17' lies against the shank 17.

45 Referring to Fig. 4, when the shank 17 is secured to a rigid support, as for instance a door frame, and the shank 17' has a load attached thereto, as for instance a door, the vertical load will be carried on the ball bearings.

50 Although a preferred specific embodiment of this invention is herein shown together with certain modified forms, it will be understood that the invention is not limited to the precise construction shown, and that some of the details may be altered or omitted without departing from the spirit of this invention.

55 60 I claim:

1. A hinge joint comprising a pair of co-acting members having respectively a knuckle-roll and a pintle-roll concentric with each other and longitudinally straight and parallel with their axis, the pintle-roll

substantially surrounding the knuckle-roll peripherally, and complementary end thrust stop means carried by the roll portions respectively, one of the stop means being detachable to permit said members to 75 be slid axially into coactive relation.

2. A hinge joint, comprising a pintle roll and a knuckle roll adapted and arranged for concentric rotative coaction one within the other throughout substantially the entire length of the hinge, one of said rolls being shouldered at one end of the hinge, and means carried by the corresponding end of the other roll and disposed transversely of the axis, said means being formed and adapted to serve as a closure for the end of the joint and also as a stop shoulder for coaction with the shouldered roll.

3. A hinge joint, comprising a pair of co-acting members having respectively a pintle-roll of semi-cylindrical shape with its free edge turned inward diametrically, and a knuckle-roll of substantially cylindrical shape with a longitudinal offset in its medial portion providing oppositely facing inner and outer shoulders adapted to serve as stops for the longitudinal edges of the pintle-roll as the hinge is closed and opened respectively.

4. A hinge joint, comprising a pair of co-acting members having respectively a pintle-roll and a knuckle-roll adapted to coact concentrically, one of said rolls having the medial portion of its free edge turned inward, in combination with an end thrust 100 stop member comprising a pair of blocks, coaxially disposed side by side, one secured to the said inwardly turned roll edge and the other secured to the other roll.

5. A hinge joint, comprising a pintle-roll and a knuckle-roll adapted and arranged for concentric rotative coaction, in combination with end thrust stop means comprising a block secured to the knuckle-roll, the pintle-roll having its inner edge turned inwardly medially and with its end formed to provide a bearing shoulder for said block to bear against.

6. A hinge joint, comprising a pair of co-acting members formed with concentric bearing rolls along adjacent edges, one of said rolls being substantially cylindrical, with the free end portion inwardly set to form a longitudinal shoulder along the roll midway between its free and supporting edges, and the other roll portion being substantially semi-cylindrical with its free edge disposed diametrically across the roll, the second roll portion being adapted and arranged to receive the inwardly set part of the first roll when the hinge is unfolded and the free edge of the diametric portion of the second roll being arranged to slide rotatively upon the inner surface of the first roll in operating the hinge.

7. A hinge-joint comprising a pair of co-acting members having respectively a pintle-roll and a knuckle-roll, each of semi-cylindrical shape and disposed longitudinally along the length of the hinge, in combination with end thrust stop means comprising a block secured to one of the rolls and having a ball-race therein, a second block secured to the other roll and having a

corresponding ball-race, and bearing balls 10 adapted to occupy the ball-races for coaction between said blocks.

Signed at Milton, Wis. this 20th day of February, 1914.

FRITZ ARTHUR ANDERSON.
